tion, coming within the scope of the appended claims.

I claim:

1. In a valve for internal combustion engines, a valve casing formed with a passage, a tapered valve seat through said casing, a tapered valve having an opening extending diametrically therethrough, said valve adapted to be oscillated to open and close the valve passage, yieldable means for holding said valve upon its seat in a position to close said valve passage and at the same time act to yieldably resist rotary and lateral motion of said valve, means for oscillating said valve to open and close said passage and means co-operating with said oscillating means whereby said valve is retracted from the seat prior to advance rotation of said valve and whereby said valve is returned to its normal position before it is advanced laterally in said casing to return to its seat.

2. In a valve for internal combustion engines, an engine cylinder, a head therefor formed with a passage opening to said cylinder, a tapered valve extending longitudinally of said passage and turnable in said head on an axis extending transversely of the cylinder, said valve being adapted to be removed and replaced from the side of the head, a spring encircling one end portion of said valve affixed at one end to the valve and at the other end to the head, said spring exerting a longitudinal pull on said valve and yieldably opposing turning movement thereof, and means for oscillating said valve.

3. In a valve for internal combustion engines, an engine cylinder, a head therefor formed with a passage opening to said cylinder, a tapered valve extending longitudinally of said passage and turnable in said head on an axis extending transversely of the cylinder, said valve being adapted to be removed and replaced from the side of the head, a spring encircling one end portion of said valve affixed at one end to the valve and at the other end to the head, said spring exerting a longitudinal pull on said valve and yieldably opposing turning movement thereof, and means for oscillating said

valve and means operating on oscillation of the valve to move the valve longitudinally in opposition to the spring on the advance stroke of the valve and permitting retraction of the valve under action of the spring on the retrograde stroke thereof.

4. In a valve for internal combustion engines, a valve casing, a tapered valve seat in said casing, adapted to have both longitudinal and rotary movement, a spring connected to said valve and acting to oppose its turning in one direction and opposing its longitudinal movement in one direction, means for oscillating said valve, and means acting on turning the valve in one direction to move it lengthwise in opposition to said spring adapted on turning the valve in the other direction to permit restoration of the valve by said spring.

5. In a valve for internal combustion engines, a valve casing, a tapered valve seat in said casing adapted to have both longitudinal and rotary movement, a spring connected to said valve and acting to oppose its turning in one direction and opposing its longitudinal movement in one direction, a disk pivoted on said valve, means for oscillating said disk, means whereby turning said disk will effect turning of the valve with lost motion of the disk at the termination of the strokes, and means acting on said disk for effecting longitudinal movement of said valve in one direction.

6. In a valve for internal combustion engines, a valve casing, a tapered valve seat in said casing adapted to have both longitudinal and rotary movement, a spring connected to said valve and acting to oppose its turning in one direction and opposing its longitudinal movement in one direction, a disk pivoted on said valve, means for oscillating said disk, means whereby turning said disk will effect turning of the valve, a cam recess on said disk, and a roller on said valve casing extending into said recess when the valve is in a normal position and adapted on turning of the disk to effect longitudinal movement of the valve.

2 Sheets-Sheet 2

This technical drawing illustrates a complex mechanical assembly, possibly a pump or valve mechanism. The drawing is oriented vertically, showing a central vertical axis and various components attached to it. Key labeled parts include:

- 27: A vertical pipe or tube extending upwards.
- 24: A component located near the top left.
- 18: A component located near the top center.
- 19: A component located on the left side.
- 21: A component located on the left side.
- 16: A component located on the left side.
- 14: A component located on the left side.
- 12: A component located on the left side.
- 30: A component located on the left side.
- 1: A component located on the left side.
- 30: A component located on the left side.
- 13: A component located on the left side.
- 26: A component located on the left side.
- 25: A component located on the left side.
- 1: A component located on the right side.
- 2: A component located on the right side.
- 5: A component located on the right side.
- 3: A component located on the right side.
- 28: A component located on the right side.
- 29: A component located on the right side.
- 7: A component located on the right side.
- 9: A component located on the right side.
- 10: A component located on the right side.
- 15: A component located at the bottom center.
- 6: A component located at the bottom center.
- 6: A component located at the bottom center.
- 16: A component located at the bottom left.
- 1: A component located at the bottom left.

The image contains two technical drawings. The left drawing, labeled 'FIG. 6.', shows a vertical pipe assembly. It features a vertical pipe 13 with a horizontal pipe 12 branching off to the left. A handle 14 is attached to the top of the vertical pipe. A sleeve 30 is attached to the horizontal pipe 12. The right drawing, labeled 'FIG. 5.', shows a handle mechanism. It consists of a vertical handle 19 attached to a vertical rod 21. The rod 21 is connected to a horizontal lever 18, which is attached to a curved handle 23. Number 14 is also present near the vertical handle 19.

UNITED STATES PATENT OFFICE.

THEOPHILUS BROWN AND CARL G. STRANLUND, OF MOLINE, ILLINOIS, ASSIGNEES
TO DEERE & COMPANY, OF MOLINE, ILLINOIS, A CORPORATION OF ILLINOIS.

WHEELED PLOW.

Application filed August 16, 1919. Serial No. 317,910.

To all whom it may concern:

Be it known that THEOPHILUS BROWN and CARL G. STRANLUND, citizens of the United States, residing at Moline, in the county of Rock Island and State of Illinois, have invented certain new and useful Improvements in Wheeled Plows, of which the following is a specification, reference being had therein to the accompanying drawing.

10 Our invention relates to wheeled plows and more particularly to that type which may be either tractor or team drawn, and the object of our invention is to provide means for a quick and effective change in some of 15 the parts whereby the plow can be adapted to attachment to a tractor, or fitted with a pole for draft animals, as will be more clearly set forth in the following specification.

Referring to the drawings in which similar numerals indicate identical parts—

Figure 1 is a plan view of a wheeled plow embodying our improvements.

Figure 2 is a front elevation of Figure 1.

Figure 3 is a detail side elevation of the 25 furrowward side of the implement showing the manner of supporting the furrowward beam on the axle.

Figure 4 is a detail in elevation of the landward side of the implement, and the 30 means employed to raise the plows from the ground.

Figure 5 is a detail section on the line 5—5 of Figure 1, and

Figure 6 is respective detail view of the 35 furrow wheel axle bearings.

The frame of the implement consists of plow beams 1 and 2 rigidly connected by braces 3 and 4, and beam 1 converging, at its forward end toward the beam 2; the forward 40 ends of the beams hold between them a clevis 5 to which the beams are rigidly secured. This clevis may be of any one of several well known types suitable for connection to a tractor. On the rear of each beam is mounted a plow body 6.

The frame is supported on a crank axle 7, rockably journaled in a bearing 8 on the beam 2. The landward end of the axle 7 is bent downwardly substantially at right 50 angles and terminates in a portion 9 extending inwardly toward the beam 2 and having mounted thereon a landwheel 10. The furrowward end of the axle 7 is also bent down-

wardly and terminates in an outwardly extending horizontal portion 11 on which is a 55 sleeve 12.

Preferably integral with the sleeve 12 is a vertical sleeve 13 in which is journaled a vertical spindle 14 having its lower end bent outwardly to form an axle 15 on which is 60 mounted the furrowwheel 16; the axle 15 is inclined as shown to give proper inclination to the furrowwheel 16 when the latter is in a furrow and the implement is horse drawn as illustrated. The upper end of the spindle 14 is a tapered square 17 on which is mounted a horizontally operating lever 18 having a square tapered socket to receive the upper 65 end of the spindle 14 which is reduced in size at its termination and is threaded, the threaded end passes through an opening in the socket of the lever 18 and is provided with a nut 19 to hold the lever 18 securely in place. Pivotaly mounted on the spindle 14 below the lever 18, is a casting 21 having 70 preferably integral therewith a horizontally disposed notched segment 22 extending landwardly with the lever 18 and adapted to be connected to the latter by a dog 23 on the lever 18. A draft tongue 24 is rigidly mounted 75 on a forward extension 25 of the casting 21.

As before stated the frame is supported on a crank axle 7, which is rockably journaled in a bearing 8 on the beam 2; on the 80 beam 1 is a swinging bracket 26 in which is rockably journaled the furrowward portion of the crank axle 7, the bracket 26 is 85 swingable by a lever 27 rigidly attached thereto and provided with the usual type of latch to engage with a notched quadrant 28 mounted on the beam 1, this mechanism is 90 operative to level the plow, and is more clearly and fully described in the application of Carl G. Strandlund, filed August 8, 1918, Serial No. 248,993, and to which reference is 95 made for further description.

The crank axle 7 is rockable to raise the plows out of operation or to lower them by means of a hand lever 29 or by traction 100 power of the landwheel 10 as fully set forth in the patent to Carl G. Strandlund No. 1,463,379, dated July, 31, 1923.

As shown in the drawing the implement is supposed to be horse drawn, but if it is 105 desired to use a tractor as the motive power
